O
FIG. 9.

INVENTOR.

Henry R. Baker
By Heratius E. Bellire

ATTORNEY.

UNITED STATES PATENT OFFICE.

HENRY R. BAKER, OF NORTH ATTLEBORO, MASSACHUSETTS, ASSIGNOR TO
R. F. SIMMONS COMPANY, A CORPORATION OF RHODE ISLAND.

BRACELET.

No. 799,133.

Specification of Letters Patent.

Patented Sept. 12, 1905.

Application filed May 23, 1905. Serial No. 261,771.

To all whom it may concern:

Be it known that I, HENRY R. BAKER, a citizen of the United States, residing at North Attleboro, in the county of Bristol and State 5 of Massachusetts, have invented certain new and useful Improvements in Bracelets, of which the following is a specification, reference being had therein to the accompanying drawings.

10 My invention relates to an improved concealed hinge or joint for bracelets, and has for its object a structure which is simple, inexpensive, and strong.

15 The invention consists in the novel form, relation, and action of the interacting parts.

In the drawings, which comprise a part of this specification, Figure 1 is perspective view of a complete bracelet equipped with my improved joint in closed position; Fig. 2, a portion 20 of the same in open position; Figs. 3 and 4, side and plan views, respectively, of the female or socket member of the joint; Figs. 5 and 6, similar views, respectively, of the tongue or male member of the joint; Fig. 25 7, a longitudinal central section of joint and the adjacent portion of the bracelet in closed position; Fig. 8, a like view of the same in open position, and Fig. 9 a transverse section of the bracelet on line xx of Fig. 1.

30 Like reference-letters indicate like parts throughout the views.

My invention is herein shown as embodied in a bracelet comprising two tubular wings A and B, in whose adjacent extremities are 35 fixed frictionally or by solder the blocks a and b , respectively. The block a terminates in two lugs a' , with an inclined or beveled intermediate recess a^3 , the whole forming a socket. The lugs are provided with perforations a^2 in 40 axial alignment with each other. The block b has a narrow projecting tongue b' , with par-

allel sides and a beveled or inclined extremity b^2 . The incline of tongue, however, is less pronounced than that of the recessed or socket portion a^3 of the joint. The tongue b' has a 45 transverse passage or opening b^3 . The lugs a' and tongue b' are assembled with the latter intermediate the former and are pivoted by a pin c , traversing the perforations a^2 and b^3 . The extremities of the pin c are concealed from 50 view by the tubular wing A, being flush with the outer surfaces of the lugs a' .

It will be noted that in closed position an angular opening d exists intermediate the extremity of the tongue b' and the seat or socket 55 a^3 . The latter, however, forms a frictional stop when the bracelet is opened its desired limit by the contact of the upper extremity of the tongue with an intermediate portion of the seat a^3 . 60

Having described my invention, what I claim is—

1. A bracelet comprising a plurality of wings hinged together, the hinge consisting of an interengaging tongue and lugs within 65 the end of one wing, and a pivot-pin traversing the tongue and lugs and terminating within said wing.

2. A bracelet comprising a plurality of wings hinged together, the hinge consisting 70 of a beveled tongue and a socket with a bevel more pronounced than that of the tongue, both within the end of one of the wings and adapted to limit the mutual travel of the tongue and socket, and a pivot-pin traversing the 75 tongue and socket.

In testimony whereof I have affixed my signature in presence of two witnesses.

HENRY R. BAKER.
